UNITED STATES PATENT OFFICE.

LUCIUS S. PRATT, OF UNION CENTER, NEW YORK.

CAR-DOOR HANGER.

970,752.

Specification of Letters Patent. Patented Sept. 20, 1910.

Application filed October 8, 1908. Serial No. 456,750.

To all whom it may concern:

Be it known that I, LUCIUS S. PRATT, a citizen of the United States, residing at Union Center, in the county of Broome, State of New York, have invented certain new and useful Improvements in Car-Door Hangers; and I do hereby declare the following to be a full, clear, and exact description of the invention, such as will enable others skilled in the art to which it appertains to make and use the same.

This invention relates to car door hangers, and has for one of its objects to simplify and improve the construction and increase the efficiency and utility of devices of this character.

Another object of the invention is to provide a simply constructed attachment whereby the door is effectually prevented from working loose at the lower edge and being thrown outward by the movements of the train or from the displacement of goods within the car.

With these and other objects in view the invention consists in general of a depending track below the floor line of the car opposite the doorway opening, a plate attached to the car door near each lower corner and each with a web extending beneath the door and a rib extending over the inner face of the door at the lower edge, an arm extending from the outer face of each plate and terminating in an inwardly extending hook bearing beneath the combined track and guide, a lug depending from the inner or rib edge of each bottom web of the plate, the lugs and arms having transverse bearing slots, and a roller between the lug and arm of each plate with journals engaging in the bearing slots and bearing upon the track guide.

The invention further consists in certain novel features of construction as hereafter shown and described, and then specifically pointed out in the claim, and in the drawings illustrating the preferred embodiment of the invention, Figure 1 is a side view of a portion of a car including one of the doorway openings and one of the doors, with the improvements applied. Fig. 2 is a section on the line 2—2 of Fig. 1. Fig. 3 is a front view enlarged of a portion of a car door at one corner, with one of the attachments applied. Fig. 4 is a section on the line 4—4 of Fig. 3. Fig. 5 is a rear view of the frame portion of the device detached.

In the operations of freight cars the tendency is for the doors to swing outwardly at the bottom under the influence of the rapidly moving trains and also by the impact of goods displaced in the cars, and to effectually prevent this tendency and to produce a door hanger which will effectually resist this movement the device herein shown and described has been produced to rigidly support the lower edge of the door from lateral movement while at the same time leaving it free to move upon its tracks.

One of the improved devices will be arranged at each lower corner of the car door, but as they are precisely alike the description of one will suffice for both.

Each car body, indicated at 10, is provided just below each doorway opening with a horizontal track each preferably formed of a section of what is known as Z bars, or with a central member 11 having reversely arranged flanges 12—13 extending in opposite directions from its opposite edges, the inner flange 12 bolted or otherwise secured to the sill member 14 of the car and the flange 13 depending below the central member and forming the combined guide track and hanger for the door. A guide track 29 is also arranged above the doorway opening, preferably of a section of the Z bar to receive the upper edge of the door.

The door which is of the usual construction is represented at 15, and bolted or otherwise secured to the door near the lower outer corners are two plates 16 having lateral wings 17—18 with a web portion 19 extending below the lower edge of the door and a vertical web 20 spaced from the wings 17—18 and bearing over the inner face of the door. The door is thus firmly supported by the plates and their webs and ribs, while at the same time the plates and their webs and ribs are firmly supported by the door.

Depending from the outer edge of each plate 16 is an arm 21 having a hook 22 at its lower end for engaging beneath the depending flange 13 of the Z bar, and with a lug 23 depending from the rib 20 or at the inner edge of the web 19, and bearing above the central member 11 of the track bar and spaced therefrom.

Formed respectively through the arm 21 and the lug 23 are transversely aligned apertures 24—25 preferably elongated, and located between the members 21—23 is a roller 26 having integral journals 27—28 engaging

in the slots 24-25. Openings 30-31 are formed in the lower sides of the slots 24-25 to enable the journals 27-28 of the rollers to be entered therein from below.

5 The improved device is simple in construction, can be adapted readily without structural changes to all the various forms and sizes of car doors in use, and operates effectually to prevent the displacement of the 10 door.

All of the securing bolts are formed with heads countersunk where exposed, and thus preventing any attempt at burglary.

What is claimed, is:—
15 In a door hanger, the combination of a track having a horizontal web and a depending guide flange at the outer edge thereof, a substantially J-shaped bracket for attachment to a door, the hook of which engages under the said guide flange, said 20 bracket being further provided at the upper

end of the arm of the hook with an inwardly extending web to bear under the door and a depending vertical web spaced from the arm of the hook and terminating above 25 the horizontal web of the track, the said arm of the hook having a lug on its inner side, said lug and the said vertical web of the bracket having each a bearing and a vertical slot leading therefrom, open at its lower end, 30 and a roller on the said horizontal web of the track and having journals in said bearings, said slots permitting the mounting and detachment of the roller when the latter and the bracket are removed from the track. 35

In testimony whereof, I affix my signature, in presence of two witnesses.

LUCIUS S. PRATT.
